United States Patent Office

Des. 227,727
Patented July 17, 1973

227,727

SEWING CADDY

Michael Beder, New York, N.Y., assignor to
Wallmounts, Inc., New York, N.Y.

Filed Aug. 2, 1971, Ser. No. 168,525

Term of patent 14 years

Int. Cl. D6—04

U.S. Cl. D6—186

FIG. 1.

FIG. 2.

FIG. 4.

FIG. 3.

FIG. 5.

FIG. 6.

FIG. 1 is a perspective view of a sewing caddy showing my new design;

FIG. 2 is a right side elevational view thereof;

FIG. 3 is a left side elevational view thereof;

FIG. 4 is a front elevational view thereof;

FIG. 5 is a reduced scale rear elevational view thereof; and

FIG. 6 is a top plan view thereof.

I claim:

The ornamental design for a sewing caddy, substantially as shown.
